George Yates, Jr., Glendale, Calif., assignor to Growth International Industries Corp., Cleveland, Ohio

Continuation-in-part of design application Ser. No. 13,761, Sept. 27, 1968, now Patent No. 216,833, dated Mar. 10, 1970. This application Jan. 30, 1970, Ser. No. 21,154

The portion of the term of the patent subsequent to Mar. 10, 1984, has been disclaimed

Term of patent 14 years

Int. Cl. D7—06

U.S. Cl. D49—29

FIG. 1 is an elevational view of a bucket showing my new design;

FIG. 2 is an elevational view looking from the right of FIG. 1, the opposite side being the same in appearance as the side shown;

FIG. 3 is a vertical sectional view taken through the center of FIG. 2; and

FIG. 4 is a bottom plan view thereof.

This application is a continuation-in-part of applicant's co-pending design application entitled bucket, Ser. No. D. 13,761, filed Sept. 27, 1968, and now patent No. D. 216,833 issued Mar. 10, 1970.

I claim:

The ornamental design for a bucket, as shown and described.
